ACTION TOY

Joseph V. Irenius, Brooklyn, N. Y., assignor to
Fisher-Price Toys, Inc., East Aurora, N. Y.

Application August 11, 1941, Serial No. 406,275

5 Claims. (Cl. 46—104)

This invention relates to action toys, and more particularly to an improved animated pull toy.

One of the objects of the invention is to provide an action toy of a type which is particularly adapted to simulate a walking or running animal such as a horse or dog, or the like, in which the activated elements of the toy are so organized and arranged as to provide walking or running simulating movements of novel and improved order. Another object of the invention is to provide an improved toy for the purpose described which is of structurally simple and rugged form and adapted to be manufactured by relatively simple and inexpensive manufacturing processes. Another object of the invention is to provide a toy of the character described which embodies improved sound producing means adapted to simulate the sound effects of a walking or running figure, in an improved manner. Other objects and advantages of the invention will appear in the specification hereinafter.

In the drawing:

Fig. 1 is a fragmentary view, partly in side elevation and partly in section of a toy of the invention;

Fig. 2 is a top plan view of a portion of the sound producing mechanism thereof; and

Fig. 3 is a side elevation of another portion of the sound producing mechanism, in disassembled relation.

The drawing illustrates the invention as comprising a pull toy of the traction wheel mounted type which includes a cart simulating portion 10 mounted for rolling movement across a floor or other supporting surface by means of traction wheels, as at 12. The cart 10 of the illustration includes a pair of spaced base sills 14 at opposite sides of the cart to the under surfaces of which is journaled an axle 15 by means of staples 16. The axle 15 is keyed to the oppositely disposed traction wheels 12, and is provided with an axially offset crank portion 18 intermediately of the sills 14.

The toy of the drawing also includes an animal simulating figure 20 which comprises a central body portion 22; a head and fore-quarter portion 24; a hind-quarter portion 26. The portions 24—26 are pivotally connected to the body portion 22 at 27 and 28 for pivotal movements relative thereto in vertical directions. The pivotal connection 27 is provided by means of a bushing 29 engaging a pair of bent wire struts 30 having ends turned into the bushing 29 and extending rearwardly therefrom at opposite sides of the toy into fixed connection with the cart

10; thus simulating customary wagon shafts. The shafts 30 are mounted in cantilever connected relation within the grooved portions of the sills 14, as at 32, and are downwardly turned as at 33 so as to engage within vertically bored portions 34 of the corresponding sills 14. Thus, it will be understood that to provide for assembly of the toy device the shafts 30 may be first mounted so as to have their forward turned end portions 10 extending into the bushing 29 from opposite ends thereof, and the rear end portions of the shafts may then be mounted within the corresponding sill members 14 by insertion of the turned portions 33 of the shafts into the bored portions of the sills until the anchoring sections 32 of the shafts rest within the longitudinally grooved portions of the sills. The body portion of the cart 10, including the floor board 11, may then be assembled upon the sills 14 by nailing or any other suitable connection method, whereupon the central and fore-quarter portions of the figure 20 will be permanently mounted upon the cart 10. The hind-quarter portion of the figure 20 may then be mounted upon the central body portion 22 by means of a pivot pin at 28.

An action transmitting link 40 of bent wire is arranged to extend between the crank portion 18 of the axle 15 and the lowermost leg portions 41—42 of the fore-quarter and hind-quarter portions respectively, of the figure 20 for imparting figure movement simulating actions to the toy figure. For this purpose the link 40 is bent at its rear end portion to form an eye 44 adapted to engage the crank portion 18 of the axle 15 in freely journaled relation thereon; and at an intermediate position the link 40 is laterally bent to provide a transversely disposed portion 45 thereof which is threaded through a suitable opening in the leg member 42. The link 40 extends forwardly from the position of the transverse portion 45 into the region of the front leg portion 41 and is laterally bent thereat for pivotal engagement with the leg portion 41 by being inserted through a suitable opening as at 46 therein. Preferably, the extreme forward end portion of the link 40 is again bent parallel to the longitudinal axis of the link, as at 47, subsequent to being mounted upon the leg 41, so as to fix the link against accidental disengagement from the leg 41.

Thus, it will be understood that the toy of the invention includes a central body portion 22 which is pivotally mounted adjacent its forward end upon the cantilever shafts 30 extending from the cart 10, and to which is articulated adjacent its

rear end a hind-quarter portion of the toy figure. The fore-quarter portion of the toy figure is also mounted in pivotable relation upon the forward end of the cantilever shafts 30, and the lower end of the fore-quarter section is pivotally connected to the strut 40 which extends rearwardly into engagement with the crank 18. Thus, the strut 40 controls the attitude of the fore-quarter section 24 with respect to its movement about its pivotal support 27, and by reason of the connection of the strut 40 to the fore-quarter section 24 the strut 40 is maintained in predetermined elevation at its forward end, and at its rear end by means of its connection to the crank 18. Thus, the strut 40 functions also as a beam for providing vertical support to the articulated hind-quarter and central body sections of the toy figure 20, through means of the mounting connection between the leg portion 42 and the strut portion 45.

Preferably, the toy cart 10 will be of the four wheel variety; having a pair of rear wheels mounted thereunder at the rear end of the cart in a manner similar to that of the mounting of the front wheels 12 under the front end of the cart as illustrated in the drawing; and the mass of the toy cart portion will be so arranged as to enable the toy cart to support the toy figure 20 in vertically elevated position above the level of the floor ahead of the toy cart through means of the cantilever mounting of the shafts 30.

Thus, it will be understood that as the toy is drawn across a floor or other supporting surface, as by means of the pull string 50, the toy figure 20 will be maintained at an elevation slightly above the floor line, as at 52. By reason of friction effects the traction wheels 12 will thereby be caused to rotate the axle 15, whereupon the crank portion 18 of the axle will cause the strut 40 to rotate at its rear end about the orbit of the crank 18 while the front end of the strut 40 will be reciprocated longitudinally of the toy. Thus, the fore-quarter section 24 of the toy will be caused to oscillate about its pivotal mounting at 27 whereby the head portion thereof will appear to bob up and down and the foot portion thereof will move in the fashion of a front foot of a running animal. Simultaneously, the rear foot portion 42 will be reciprocated longitudinally of the toy by reason of the longitudinal component of the movement of the strut 40, but the vertical component thereof in the region of the connection 45 will cause the hind-quarter 26 of the toy figure 20 to be simultaneously oscillated in vertical directions. Thus, the hind-quarter and central body portions of the toy figure 20 will be caused to so move as to cooperate with the movement of the fore-quarter portion 24 so as to simulate in unusually effective manner the body movements of a running or walking horse or dog or other quadruped.

To provide suitable sound effects in connection with operation of the toy a lever arm 60 (Figs. 1 and 2) carrying a striker ball 62 is provided with a laterally bent opposite end portion 64 for pivotal mounting upon a suitably apertured portion of one of the sills 14. The lever 60 is formed with a looped intermediate section 66 adapted to encompass the orbit of the axle 15 and to thus lead into a transverse cam section 67 from which the main body portion leads to the striker 62. A lever actuating cam 68 (Figs. 1 and 3) is centrally apertured at 69 for mounting upon the axle 15 in keyed relation thereon. The cam 68 is of plate-like form and is generally rounded but

formed with a pair of protruding edge portions 70 which extend beyond the radial extent of the major rounded body portion of the cam so as to be adapted to function to lift against the transverse portion 67 of the striker lever when rotated by the axle into contact therewith. Thus, upon relatively rapid movement of the toy across a floor or other supporting surface, the cam portions 70 will be caused to move against the lever 60 in such manner as to throw the latter upwardly about the axis of its pivotal connection at 64 so that the striker 62 hammers against the wooden floor member 11 of the cart with a clattering sound effect closely simulating the hoof beats of a running horse or the like. It will be understood that the relative spacing of the cam portions 70 of the plate 68 will be regulated so as to provide any desired form of timing of the hoof beat effects; and that although only one form of the invention has been shown and described in detail it will be apparent to those skilled in the art that the invention is not so limited but that various changes may be made therein without departing from the spirit of the invention or the scope of the appended claims.

1. An action toy including a support, cantilever arm means extending rigidly from said support, an animal-simulating figure comprising a body section and fore and hind quarter sections pivoted thereto, said body section being pivotally supported by said arm, crank means mounted upon said support, means on said support for rotating said crank means, and beam means pivotally connected to said crank means and to said fore and hind-quarter sections, the latter two pivotal connections being spaced from the pivotal connections between the animal body section.

2. An action toy including a support, cantilever arm means extending rigidly from said support, an animal-simulating figure comprising a body section, fore and hind quarter sections pivotally connected to the fore and rear portions of said body section, the body section and the fore quarter section being jointly pivotally supported by said arm means for independent pivotal movement, the pivotal connection between said body section and said hind quarter section being free to move about said joint pivotal connection, said front and hind quarter sections having depending leg portions, a crank on said support and a beam element pivotally connected thereto, and means on said support for rotating said crank, said beam element having pivotal connection with both of said leg portions at spaced points along said beam element.

3. An action toy including a support, cantilever arm means extending rigidly from said support, an animal-simulating figure comprising a body section, fore and hind quarter sections pivotally connected to the fore and rear portions of said body section, the body section and the fore quarter section being jointly pivotally supported by said arm means for independent pivotal movement, the pivotal connection between said body section and said hind quarter section being free to move about said joint pivotal connection, a crank on said support and a beam element pivotally connected thereto, and means on said support for rotating said crank, said beam element having pivotal connections with said fore and hind quarter sections spaced from their respective pivotal connections with said body section.

4. An action toy including a support, cantilever arm means extending rigidly from said support, an animal-simulating figure comprising a

body section, fore and hind quarter sections pivotally connected to the fore and rear portions of said body section, the body section and one of said quarter sections being jointly pivotally supported by said arm means for independent pivotal movement, the pivotal connection between said body section and the other of said quarter sections being free to move about said joint pivotal connection, said front and hind quarter sections having depending leg portions, a crank on said support and a beam element pivotally connected thereto, and means on said support for rotating said crank, said beam element having pivotal connection with both of said leg portions.

5. An action toy including a support, cantilever arm means extending rigidly from said support, an animal-simulating figure comprising a

body section, fore and hind quarter sections pivotally connected to the fore and rear portions of said body section, the body section and one of said quarter sections being jointly pivotally supported by said arm means for independent pivotal movement, the pivotal connection between said body section and the other of said quarter sections being free to move about said joint pivotal connection, a crank on said support and a beam element pivotally connected thereto, and means on said support for rotating said crank, said beam element having pivotal connections with said fore and hind quarter sections spaced from their respective pivotal connections with said body section.
